UNITED STATES PATENT OFFICE.

LESTER H. GIBSON, OF BROOKLINE, MASSACHUSETTS, ASSIGNOR TO GIBSON-HOLLISTER MANUFACTURING COMPANY, OF BOSTON, MASSACHUSETTS, A CORPORATION OF MASSACHUSETTS.

IGNITION DEVICE.

1,224,296.

Specification of Letters Patent.

Patented May 1, 1917.

Application filed April 24, 1915. Serial No. 23,585.

To all whom it may concern:

Be it known that I, LESTER H. GIBSON, a citizen of the United States, residing at Brookline, in the county of Norfolk and State of Massachusetts, have invented certain new and useful Improvements in Ignition Devices; and I do hereby declare the following to be a full, clear, and exact description of the invention, such as will enable others skilled in the art to which it appertains to make and use the same.

The present invention relates to ignition devices, and more particularly to spark plugs employed for exploding a charge of gas in the combustion chamber of an internal combustion motor.

In certain types of spark plugs the spark occurs at the opening of a chamber formed in the spark plug, igniting a small body of gas contained in the chamber, which in turn ignites the main body of gas in the combustion chamber. This type of plug is satisfactory in that the passage of gas past the sparking points tends to clean the points and prevent the accumulation of oil or carbon thereon. In spark plugs of this type, however, it frequently happens that a body of inert or burnt gas collects in the inclosed chamber and prevents the formation of a body of combustible gas about the spark gap.

The object of the present invention is to provide certain improvements in a spark plug of this type to permit the passage of combustible gas to the spark gap and insure that the main body of gas shall be exploded by the spark.

With this object in view the features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 represents a longitudinal section in elevation of a spark plug embodying the features of the invention; Fig. 2 is a bottom plan view of the plug shown in Fig. 1; Fig. 3 is a detail showing a section of the lower end of the plug and illustrating the passage for the gas; Fig. 4 is a detail illustrating the method of forming the insulating shell of mica for the high tension electrode; Fig. 5 is a detail showing the method

of inserting the mica shell in the porcelain bushing; Fig. 6 is a detail illustrating a modified form of the plug; and Fig. 7 is a plan view of the plug shown in Fig. 6.

The spark plug shown in the illustrated embodiment of the invention consists of a metal shell 1 having a depending annular skirt 2 which is threadedly received in the cylinder of the internal combustion motor. The skirt of the plug forms a substantially inclosed chamber 3 having side walls which converge to a restricted orifice 5. A small body of combustible gas collects in the chamber 3 and is exploded by a spark in the orifice 5, this body of gas then rushing out through the orifice and exploding in turn the main body of gas in the combustion chamber. The usual high tension electrode 6 is mounted in a porcelain bushing 7 and is connected at its upper end with a terminal cap 8. The insulator bushing 7 is secured in the metal shell by a gland 10 threadedly engaging with the metal shell 1 and yieldingly clamping the bushing in the shell through copper asbestos washers 12. The high tension electrode 6 is provided with an insulating shell consisting of a sheet of mica 14 wound cylindrically thereon. In forming the mica shell, as shown clearly in Figs. 4 and 5 of the drawings the sheet of mica is wound closely upon a mandrel 13 having a longitudinal slot 15, and the mandrel and shell are then inserted within the porcelain bushing, the mandrel being then withdrawn to permit the insertion of the high tension electrode 6. A seal 16 of permanently flexible cement surrounds the electrode and serves to prevent the passage of gas from the combustion chamber between the electrode and insulating members. The lower end of the electrode 6 extends into the orifice 5 and the spark passes between the electrode and the annular rim of the skirt 2 of the metal shell.

It frequently happens in spark plugs of this type that a body of inert gas collects in the chamber 3 and upon the occurrence of the spark the resulting explosion is not sufficient to properly ignite the main body of gas in the combustion chamber owing to the insufficient amount of combustible gas in proximity to the spark gap. To this end the present invention contemplates the provision of gas passages formed in the lower face of the skirt 2 and intersecting the spark gap to

permit the access of combustible gas to the spark gap. In the illustrated embodiment of the invention a slot or passage 17 extends transversely across the lower face of the skirt and intersects the spark gap, as shown clearly in Figs. 1 and 2. In the illustrated embodiment of the invention one of the 5 sparking points is conveniently formed by a non-corroding ring 18 of nickel which is inserted in the lower face of the skirt and forms the rim of the orifice 5. The transverse slot or passage 17 extends across the face of the skirt and the ring 18, and the spark passes between the electrode 6 and the 10 face of the ring 18 across the passage. 15

In the modified construction shown in Figs. 6 and 7, the skirt 2, the electrode 6, and the slot 17 are formed in the usual manner and the opposed sparking points are conveniently formed by metal pins 20 secured 20 in the skirt 2 and disposed upon opposite sides of the electrode 6 to cause the spark to pass across the transverse slot 17.

While it is preferred to employ the specific 25 construction and arrangement of parts shown and described, it will be understood that this construction and arrangement is not essential except so far as specified in the claims, and may be changed or modified 30 without departing from the broader features of the invention.

The invention having been described, what is claimed is:

1. A spark plug comprising a metal shell 35 having a depending annular skirt, the bottom of which is thickened to form a conical inclosed chamber having the side walls converging to a single substantially circular restricted orifice at its bottom, the inner face 40 of which orifice forms one of the sparking points of the spark gap, an insulating bushing secured in the shell, and an electrode extending through the bushing and having a 45 sparking point located in the orifice, the restricted orifice compelling the ignited gas in

the chamber to pass and clean the sparking points, and the lower face of the shell forming a substantially flat annular surface around the orifice and being provided with a slot cut therein and intersecting the orifice 50 near the sparking points to permit free access of combustible gas to the sparking points.

2. A spark plug comprising a metal shell 55 having a depending annular skirt forming an inclosed chamber with a single restricted orifice at its bottom, the inner face of which forms one of the sparking points, an insulating bushing secured in the shell, and an electrode extending through the bushing and 60 having a sparking point located in the orifice, the passage of the ignited gas past the sparking points tending to clean them, and the lower face of the shell being provided with a slot cut therein and intersecting the 65 orifice near the sparking points to permit free access of combustible gas to the sparking points.

3. A spark plug comprising a metal shell 70 having a depending annular skirt, the bottom of which is thickened to form an inclosed chamber with a single restricted orifice at its bottom, the skirt forming a substantially flat annular bottom surface for the plug around the orifice, an insulating bushing secured in the shell, an electrode extending through the bushing and having a sparking point located in the orifice, and a non-corroding ring inserted around the mouth of the orifice and flush with the bottom surface 75 of the plug to form the other sparking point, the inclosed chamber compelling the ignited gas to pass and clean the sparking points, and the lower face of the shell being provided with a transverse slot cut therein and 80 partially through the ring to intersect the orifice near the sparking points and permit the free access of combustible gas to the 85 sparking points.

LESTER H. GIBSON.
